UNITED STATES PATENT OFFICE.

TRUMAN WOLCOTT, OF STOWE, ASSIGNOR TO HIMSELF AND GEORGE T. WOLCOTT, OF MARLBOROUGH, MASSACHUSETTS.

LASTING-MACHINE.

Specification forming part of Letters Patent No. 39,870, dated September 8, 1863.

To all whom it may concern:

Be it known that I, TRUMAN WOLCOTT, of Stowe, in the county of Middlesex and State of Massachusetts, have invented a new and Improved Lasting-Machine; and I do hereby declare that the following is a full, clear, and exact description of the same, reference being had to the accompanying drawings, making a part of this specification, in which—

Figures 1 and 2 are plans or top views of my invention, the ring on the top of the machine being removed in Fig. 2; Fig. 3, a vertical section of the same, taken in the line α α , Fig. 1; Fig. 4, a detached perspective view of one of the slides and crimping-blocks pertaining to the same.

Similar letters of reference indicate corresponding parts in the several figures.

This invention relates to a new and improved machine for adjusting uppers on lasts, as hereinafter fully shown and described, whereby the work may be done in a superior manner and very expeditiously.

To enable those skilled in the art to fully understand and construct my invention, I will proceed to describe it.

A represents an upright framing, which may be constructed in any proper manner to support the working parts of the machine; and B is a treadle, which is secured in the lower part of the framing, and has a weight, C, on one end of it, as shown clearly in Fig. 3. This treadle B has a vertical rod, D, connected to it, said rod extending upward a suitable distance. The use of this rod will be presently shown. On the upper part of this framing A there is a circular plate, E, which has a number of radial grooves made in it to receive slides F, which are allowed to work freely in their grooves, and have vertical pins a near their outer ends, on which friction-rollers b are placed, said friction-rollers being fitted within slots c , which are made eccentrically in a ring, G, placed on the circular plate E in such a manner that it may turn freely thereon. By turning this ring G the slides F will be moved inward and outward from the center of plate E in consequence of the friction-rollers b fitting within the eccentric slots c of the ring G. This will be fully understood by referring to Figs. 1 and 2.

To the inner ends of six of the slides F

there are secured adjustable crimping-bars, which are designated by d d , e e , f f . The bars d d are opposite each other, and have their outer or faced sides curved to conform to the shape of the sides of the last, while the bars e e are curved to conform to the heel and the bars f f to conform to the toe of the last. Two of the slides have hooks g g attached to them, and a hook, h , is attached to the plate B between the bars f f . The hook h is somewhat elastic or yielding, and to the inner ends of the slides F, which have the toe-bars f attached, there are secured elastic plates i i , one to each. The hooks g g , it will be seen by referring to Figs. 1 and 2, are between the bars d d and e e . To the upper surface of each crimping-bar there is attached a metal plate, j , the inner edges of which project slightly over or beyond the inner or face sides of the crimping-bars.

The operation is as follows: The upper is placed on the last, its front part drawn over the toe of the same by means of pinchers, and secured by a peg. The last, which is shown in red, is then inverted and secured to the upper end of the rod D in any proper way. The operator then depresses the elevated end of the treadle B, and thereby draws down the last, the central part of the plate F having an oblong opening, k , made in it to receive the last, the sole of which is brought down just below the plates j of the crimping-bars. The operator then turns the ring G sufficiently to cause the hooks g g to grasp the shank of the last and adjust it in proper position, the toe of the last being properly retained and held by the elastic plates i i and hook h . These plates and hook constitute an important feature of the invention, as they insure a proper adjustment of the last and retain it when properly adjusted. When the last is thus adjusted, the operator removes his foot from the treadle B and turns the ring G so as to force all the crimping-bars d d , e e , f f inward and the upper will be snugly drawn or fitted to the last, the plates j forcing the edge of the upper over the edges of the sole of the last, and the former is then pegged to the latter. By having two toe-crimping bars, f f , and two heel-crimping bars, e e , the work is done much better than it can be done with one of each only. When the ring G is turned so as to throw outward the crimping bars and hooks

g g, and the last is released, the weight C will throw up the rod D to its original position.

The ring G may be operated by gearing, if desired.

I do not claim the sliding crimping-bars, broadly, or irrespective of their arrangement and the manner in which they are operated, for such device has been previously used; but

I do claim as new and desire to secure by Letters Patent—

1. The heel, side, and toe crimping bars *d d, e e, f f*, with plates *j* attached, arranged as shown, and operated by the ring G, provided with eccentric slots *c*, in which pins or friction-rollers on the slides F are fitted, substantially as and for the purpose set forth.

2. The hooks *g g*, arranged as shown, to operate in connection with the crimping-bars, as and for the purpose set forth.

3. The elastic plates *i i*, in connection with the hooks *h*, to operate in connection with the crimping bars, as and for the purpose specified.

4. The loaded treadle B, with rod D attached, in combination with the crimping-bars, all arranged to operate substantially as and for the purpose specified.

TRUMAN WOLCOTT.
